[57] CLAIM

The ornamental design for a bottle or the like, as shown and described.

DESCRIPTION

FIG. 1 is a front elevational view of a bottle or the like showing my new design;

FIG. 2 is a rear view of the design of the bottle of FIG. 1; and

FIG. 3 is a modified form of the design, namely, a view like FIG. 1 but with the lei removed.

FIG. 1.

FIG. 2.

FIG. 3.
